UNITED STATES PATENT OFFICE.

GUY W. BLAKELY, OF SAXMAN, KANSAS.

PERPETUAL CALENDAR.

1,169,230.

Specification of Letters Patent.

Patented Jan. 25, 1916.

Application filed February 27, 1915. Serial No. 11,014.

To all whom it may concern:

Be it known that I, GUY W. BLAKELY, a citizen of the United States, residing at 5 Saxman, in the county of Rice and State of Kansas, have invented certain new and useful Improvements in Perpetual Calendars, of which the following is a specification, reference being had to the accompanying drawings.

10 This invention relates to certain improvements in perpetual calendars and has relation more particularly to a device of this general character especially designed and adapted for use in connection with a writing implement or the like; and an object of 15 the invention is to provide a calendar of this character having novel and improved means whereby the same may be operated with convenience and facility and which 20 may be effectively maintained in applied position.

The novel features of the invention will be carefully defined in the appended claim.

In order that my invention may be the 25 better understood, I will now proceed to describe the same with reference to the accompanying drawings, wherein—

Figure 1 is an elevational view of a calendar constructed in accordance with an 30 embodiment of my invention in applied position; Fig. 2 is a longitudinal sectional view of the device as shown in Fig. 1, the coacting implement being shown in elevation; Fig. 3 is a diagrammatic view illustrating the arrangement of the blocks containing the month identities; Fig. 4 is a 35 diagrammatic view illustrating the blocks containing the date identities; and Fig. 5 is a diagrammatic view illustrating the 40 blocks containing the day identities.

As disclosed in the accompanying drawings, 45 1 denotes an elongated tubular member preferably of a transverse diameter slightly in excess of the implement P to which it is to be applied and is provided at its opposite extremities with the diametrically opposed resilient fingers 2 adapted to frictionally engage the periphery of the implement and to maintain the tube in applied 50 position thereon. Also carried by one end portion of the tubular member 1, preferably the inner extremity when applied, is the clip 3 adapted to coact in a conventional way with a pocket or the like, for a purpose 55 which is believed to be clearly apparent to those skilled in the art to which my inven-

tion appertains. Rotatably engaged with the upper extremity of the tubular member 1 are the sleeves 4 and 5, each of said sleeves, as herein disclosed, being provided with an 60 annular bead 6 adapted to be received within an annular groove 7 suitably produced in the tubular member 1, whereby each of the sleeves is effectively maintained against longitudinal displacement relative to the tubular member 1 but capable of free axial rotation 65 therearound.

The outer extremity of the tubular member 1 is divided by the lines or demarcations 8 into a plurality of annular fields, each of 70 said fields being divided by the longitudinally disposed lines 9 into a plurality of blocks 10, said blocks of one field being offset relative to the blocks of the adjacent field, and said blocks have positioned there- 75 in the indications 11 denoting a month of a year together with the days of said month. The fields afforded by the lines 8 are surrounded by the sleeve 4, said sleeve being provided in its opposite end portions with 80 the openings 12 in offset relation and adapted to register with the blocks 10, for a purpose which is believed to be self-evident, and it is to be particularly noted that with 85 one of the openings in register with a coacting block, the indications 11 visible through the second opening are sufficiently unintelligible or inaccurate as to permit the user to readily determine which of the openings 12 is in use. 90

The inner sleeve 5 is divided by the lines or demarcations 14 disposed longitudinally of the tubular member 1 into the fields 15, seven in number, and each of said fields being identified, as at 16, as a day of the 95 week, said identities being arranged in proper sequence. The periphery of the tubular member 1 immediately adjacent the inner sleeve 5 is divided by the longitudinal and annular lines or demarcations 17 100 into the blocks 18 adapted to align with the fields 15 and have positioned therein in proper sequence the numerals 19, to denote the day of the month. The extreme inner extremity of the tubular member 1 has its 105 periphery blank in order that suitable advertising matter or the like may be placed thereon.

It is thought that the operation of my improved calendar is self-evident without 110 the necessity of a detailed description thereof.

2
 The tubular member 1 together with the sleeves 4 and 5 is preferably produced from a suitable metal and the various indications carried by the tubular member 1 and the sleeve 4 are preferably printed upon a paper strip pasted thereon and incased within suitable transparent shields 20, for a purpose which is believed to be self-evident.

From the foregoing description, it is thought to be obvious that a perpetual calendar constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

25 I claim:

The herein described calendar attachment for pencils and the like, which includes a tubular member provided at its extremities

with means for resilient frictional engagement upon the pencil, monthly indicia arranged on said tubular member, a pair of sleeves of equal diameter engaged upon said tubular member for independent rotation thereon, the opposed ends of said sleeves being in abutting engagement, said sleeves being also provided with means upon their corresponding ends co-operatively engaged with means on said tubular member whereby the sleeves are held against relative longitudinal shifting movement thereon, one of said sleeves being provided with sight openings through which the monthly indicia on the tubular member may be viewed, and the other of said sleeves being provided upon its periphery with daily indicia, said tubular member being further provided upon its medial portion with numerals indicative of a calendar month with relation to which the indicia upon the latter sleeve are adapted to be disposed.

35 40 45 50
 In testimony whereof I hereunto affix my signature, in the presence of two witnesses.

GUY W. BLAKELY.
